UNITED STATES PATENT OFFICE.

JAMES E. EVANS, OF CHICAGO, ILLINOIS.

DEVICE FOR REENFORCING MOLDS.

Application filed July 21, 1924 Serial No. 727,209.

To all whom it may concern:

Be it known that I, JAMES E. EVANS, a citizen of the United States, residing at Chicago, in the county of Cook and State of Illinois, have invented a new and useful Device for Reenforcing Molds, of which the following is a specification.

My invention relates to said molding, and its object is to provide a means of easily 10 and cheaply reenforcing the surface of the mold against cutting and washing by the inflowing metal.

My invention is illustrated in the accompanying drawing, in which like letters of 15 reference refer to like parts throughout the several views, and in which Figures 1, 2 and 3 are views in perspective of different forms of my device, and Figure 4 is a view in section of a drag or nowel in which the sand 20 has been rammed and from which the pattern has been drawn leaving the mold, showing the mold reenforced at several points in accordance with my invention.

In sand molding, although facing sand 25 is used, the surface of the mold is liable to be cut or washed by the molten metal flowing into the mold. This is especially liable to happen at the points or corners of the mold.

30 To prevent such cutting or washing of the mold by the inflowing metal, my invention provides a method of facing such portion of the surface of the mold as may be desired, particularly the places where the danger of cutting or washing is greatest, with thin sheet metal, in such a way that said reenforcing facing material may be held firmly in place.

The device which I use for this purpose is 40 preferably made of tin, although it may be made of wrought iron or any other suitable metal. It is made of sheet metal, from which it is adapted to be stamped, and it comprises a relatively large leaf of sheet metal, adapted to rest upon the surface of the mold, and one or more thin prongs extending at right angles from said leaf and adapted to be pressed into the sand and so hold in place on the surface of the mold 45 said leaf, which, because of its large extent, will retain in place a considerable portion of the surface sand of the mold.

When the mold has been completed, the 50 pattern drawn, the surface of the mold properly reenforced in accordance with my invention and the parts of the flask as-

sembled for the casting, the metal flowing into the mold will not wash or cut its surface, the thin sheet metal leaves resting on the surface of the mold and retaining the sand will readily fuse in the casting, and the thin, flat prongs, which are pressed into the sand and hold the surface reenforcing leaves in place, can be readily chipped off the surface of the casting when it is removed from the mold.

In Figure 1 *a* is the thin, flat sheet metal leaf adapted to rest on the surface of the mold. It is made of relatively large area, so as to reenforce a considerable portion 70 of the surface. In the form of the device shown in said Figure 1, I have shown a thin flat prong *b* and two additional shorter prongs *c* adapted to be pressed into the sand and more securely hold the device in place to 75 protect the surface of the mold.

In Figure 2 *a* is the surface protecting leaf, and *b* is the prong, *a* being formed in two parts at right angles to each other in the same plane by cutting the sheet of 80 metal of which the device is made longitudinally from the top about half way down, then bending the sheet longitudinally to form an angle of 90 degrees and then bending over the two portions of the upper 85 part of the sheet as shown, thus also forming the prong *b* by the longitudinal bend down its center into two sides at right angles to each other. This form of my device would be particularly adapted for a 90 corner in a mold.

In Figure 3 another form showing the leaf *a* also in two parts, and the prong *b*, bent in the same manner as in Figure 2, is 95 shown.

The prongs may, however, be broader or narrower and may be formed all in one plane, as shown in Figure 1, or in two planes, as shown in Figures 2 and 3, and the surface reenforcing leaves may be formed 100 as illustrated or in other forms, as convenience suggests, without departing from the spirit of my invention, which consists in providing for use in sand molds a surface facing element of thin sheet material 105 which is readily fusible in the casting and is provided with integral means for engaging with the sand and holding the surface facing element in place.

It will be obvious that by reason of the 110 relatively large leaf portion of the device, the surface of the mold may be properly

reinforced with the use of a relatively small number of the devices, without the workmen expending much time in placing the devices. It will also be obvious that, by reason of the light construction of the prong or prongs, they will be easily chipped off from the surface of the casting when it has been removed from the mold.

It will be understood that my device is adapted for use in any portion of the mold. In Figure 4 several of these devices are shown as inserted in the portion of the mold which is formed in a drag, but they would be used in the same way in the portion of a mold which might be formed in the cope or in a cheek.

Having now described my invention, what I claim as new and desire to secure by Letters Patent of the United States is:

20 1. A device of the class described comprising a prong member with two sides disposed at an angle to each other, and a leaf member formed by the prolongation of said sides, the separation of them longitudinally 25 and the bending of them at substantially an angle of 90 degrees to said prong.

2. A device of the class described made

of one piece of thin sheet metal and comprising a head adapted to rest on the surface of the sand and retain the same in place, and a pointed prong at the edge of said head and substantially at a right angle thereto adapted to be imbedded in said sand and thereby retain said head in place.

3. A device of the class described made of one piece of thin sheet metal and comprising a head adapted to rest on the surface of the sand and retain the same in place, and a plurality of pointed prongs at the edge of said head and substantially at right angles thereto adapted to be imbedded in said sand and thereby retain said head in place.

4. A device of the class described made of one piece of thin sheet metal, comprising a head and a pointed prong, the head comprising members disposed at an angle to each other in the same plane, and the prong extending from the edge of the head at substantially a right angle thereto and having its sides disposed at an angle to each other.

JAMES E. EVANS.
